LYNN EVANS, OF CORTLAND, NEW YORK, ASSIGNOR TO THE BREWER-TITCHENER CORPORATION, OF CORTLAND, NEW YORK, A CORPORATION OF NEW YORK.

SELF-RAISING VEHICLE TOP.

Application filed March 23, 1926. Serial No. 96,857.

This invention relates to automobile tops and is characterized by an improved means for automatically raising a bipartite main bow. In the present disclosure my novel devices are 5 shown as applied to a top preferably comprising a forward or outrigger hoop section and a rear section equipt with a set of side-rail slats respectively adjoined to hoop legs by knuckle stop joint means, the rear ends of 10 the side-rail slats being pivotally carried by support standards in overhung fashion through the medium of a pair of companion links, such that when the top is allowed to extend into open position, both bipartite bow 15 sections fall in substantial horizontal alignment over the trim line of the vehicle body.

An important feature of the present invention resides in providing certain of such or similar top frame elements with suitable rock- 20 er members between which is mounted a resi- 25 silent tensioning device initially stretched to exert a pull therebetween, adapted to furnish motive power for automatically extending the pivotally connected frame-work and cause it to function as an improved self-raising top.

Embodying herein are further features of structure and organization to accomplish the foregoing and related purposes, all of which 30 will be set forth in detail hereinafter.

Reference is had to the annexed one sheet drawing which is illustrative of a specific embodiment of my invention, like characters of reference indicate like parts throughout the 35 several views; and in which drawings:—

Fig. 1 shows a sectional elevational view as seen from the interior of a top supporting structure embodying my improvements as applied to an automobile body, the top being 40 here shown in its raised or extended position.

Fig. 2 shows the position occupied by the top elements after the structure has been crashed into its fully collapsed position, certain top elements being broken away to better 45 illustrate the disposition of parts.

Fig. 3 represents a detail of certain top parts as taken in section along line 3—3 of Fig. 1.

Fig. 4 is a fragmental side view similar to Fig. 1 showing an enlarged detail of the resi- 50 silent element which furnishes motive power for my self raising top.

Fig. 5 is a view similar to Fig. 4 but shows a modified actuating spring and linkage arrangement therefor for resiliently manipulat- 55 ing the top.

Fig. 6 represents still another modification showing the use of a non-metallic or rubber-like elastic element for exerting the required tension for self-raising top purposes. 60

A particular type of conventional top structure will first be described in order to more clearly illustrate how my automatic or self-raising features may be embodied therein it being understood that the same underlying principles are also readily applicable to many other types of tops. 65

Referring now in detail to the drawings, the cover fabric designated in its entirety by the numeral —1—, is appropriately stretched over said top structure in the customary manner, and except for the side-rails and brace-links, the frame work in the present disclosure is shown as constructed of the usual tubular bow sockets. The top structure as a 70

whole may be pivotally supported by a single set of standards each preferably comprising metallic bow sockets such as 2B, which may be respectively pivoted upon the outer sides of the body or tonneau 3 by means of the props or fulcrum irons such as 4. Said standards are preferably inclined rearwardly and upwardly in the direction of the trans- 75

verse rear corner of the top as indicated in Fig. 1, and these sockets may be bridged by a transverse crown member 2C to form a unitary rear hoop 2. The upper end portion of each such standard socket 2B is shown as 80

equipt with a suitable pivot clip 5 which in the present disclosure is used to mount the leg ends 6C of the support bow 6B. This support hoop preferably comprises a set of bow socket members 6A which are attached to the respective leg ends of the bow crown 6B. In raised top position, said bow sockets are pref- 85

erably inclined upwardly and forwardly with 90

95

respect to the standards 2B, while intermediate the ends of each of the socket members 6A, a pivot 7 is provided to carry the side-rail section of my bipartite main bow. The 5 socket element embraced between its pivots 5 and 7 and identified as 6C, may be made to function as a guide link for the side-rail adjoined thereto. Said bipartite main hoop designated in its entirety as 8, comprises two 10 adjoined sections, namely the complementary side-rail elements such as 8A, and the outrigger crown 8D having leg ends such as 8B. When the top is extended, the side sections of this bow are intended to lie on a level substantially parallel to that of the respective longitudinal trim line 3B of the body sides. Each 15 forward end of the side-rails is provided with a rule or other suitable knuckle stop joint means 8C adapted to break downwardly as indicated, and these joints respectively carry the cooperating free end of the inversely mounted bow legs 8B of the outrigger hoop.

Referring further to the novel linkage 20 which serves to pivotally support my articulated main bow sections 8A and 8B, it will be observed that the rear portion of each side-rail 8A is pivotally mounted upon its support 25 bow socket 6A which socket end is in turn pivotally attached to its standard 2B. In addition to the described guide-link element 30 6C for each side-rail, there may be provided a companion brace link 10 of which one end portion is joined to one of the side-rails 8A 35 by the pivot 11, while the other end of the rearwardly and downwardly disposed link 10 is joined to its adjacent standard 2B by the pivot 12.

The link portion 6C of the pivoted end of 40 the support bow 6B together with the link 10 act conjointly as a unitary guide means to swing the former into either its collapsed or extended position with respect to the latter. Furthermore, as is shown in Fig. 2, both rail 45 ends of said links 6C and 10 are made to swing upward about their respective spaced pivots 5 and 12 and away from the standard fulcrum prop 4. Hence when the bipartite main bow 8 is fully crashed, its side-rails are 50 brought into juxtaposition alongside the respective standards while the support bow will then fall into a similar aligned relation in the fashion indicated.

My top may further be equipped with one or 55 more intermediate bows, and to this end the bow socket end 14B of the forward intermediate bow 14 may bridge the side-rails 8A and be mounted thereon by the offset pivots such as 14A. These joints are preferably placed 60 intermediate the joint 8C and the support bow pivots 7 and in raised position of the top, the leg ends of said bow 14 may then be inclined in a substantially parallel relation to that of the complementary support bow 65 6A.

Fig. 3 discloses in detail, the preferred lateral disposition of my linkage arrangement. It will be seen that upper end portion of the offset brace-link 10 may be mounted adjacent to the outermost face of one of the 70 side-rail slats 8A while the lower end thereof may be clip pivoted in alignment with the center of its standard 2B. The support bow socket 6A forming the guide-link portion 6C, is similarly disposed and made to lie in a substantially common vertical plane with that of its standard 2B, while the support bow leg 6A is preferably secured to the outer face of the slat iron side-rail 8A as shown.

The various intermediate bows may be interconnected with respect to the outrigger section 8B by means of suitable link means such as shown in Fig. 1, where the rear link element 15 is pivotally connected to the bow socket leg 6A at the point 15A and thence extends forwardly to the pivot 15B carried by the bow socket 14B. A second or forward link strap 16 similarly connects the pivot 16A with the pivot 16B, the latter being carried by the outrigger leg 8B and thus serves to impart concordant 90 action to the component top elements while they are being manipulated.

Referring now to the means by which the necessary motive energy for self-raising top purposes is stored, it will be observed that in Fig. 1, the rear link 15 may be formed into bell-crank shape to constitute an apertured dependant or primary lever arm 15C adapted to turn about the pivot 15A, also that the forward intermediate bow socket 14B or other appropriate top element may likewise be equipped with an apertured extension constituting a cooperating lever or rocker arm member 14C adapted to fulcrum about the pivot 14A and move in coordinated relation to the 105 arm 15C. Between these lever arms, a suitable resilient means may be floatingly stretched which in the case shown in Figs. 1 and 4, comprises a helical or coiled tension spring 17A having pivotal hook ends that respectively cooperate with said apertures formed in the stretching members 15C and 14C, the latter members being preferably equipped with an intermediary swivel link 17B.

When the intermediate bow 14 is swung 115 through the full range of top movement from its extended forward position into its fully collapsed position, this will cause the extension member 14C to rock through a correspondingly wide angular range, such that in either of its extreme positions, the swivel link 17B will be drawn into virtual alignment with respect to the longitudinal axis of said extension member and as a consequence the spring 17A can in such relation merely exert a relatively small effective lifting moment or purchase about the side rail pivot 14A. For any intermediate position however, and especially when the bow socket 14B is swung into an approximately right angled relation with 120 125 130

respect to the axis of the side-rail 8A, the leverage afforded by the extension member 14C will thereby be materially augmented. Obviously the primary rocker 15C engaging the 5 other end of the spring 17A will likewise be carried through a considerable angular swing movement whenever the top is collapsed, but the disposition given to the pivoted said arm 15C is such that the spring is allowed to work 10 with a substantial leverage or purchase throughout the entire range of top movement and particularly so whenever the top is fully extended or fully collapsed, that is to say at the very time when the extension member 14C 15 is not functioning to best advantage. Furthermore, while passing through their intermediate or partially collapsed top position, the complementary stretching members are made to cooperate in a novel manner in that 20 all supplemental lifting effort afforded by the member 14C is always added positive-wise to the effort exerted by the primary stretching member 15C and these component purchase actions are at no time allowed to oppose or 25 partially neutralize each other.

When the top is extended, the spring element is initially tensioned between its stretching members to a lesser extent than applies when the top is collapsed, as will be apparent 30 from Figures 1 and 2. During the collapsing operation, the required amount of motive power is stored within said resilient tensioning means to be subsequently utilized for self-raising top purposes. The disposition of my 35 two pivoted stretching members is such that while the top is being crashed, these stretching members are given a certain amount of separating movement in opposite or contrary directions. It will be obvious that the pivot 40 pins of stretching members are so disposed that an unobstructed and straight line relation is maintained between the spring ends, all without need of subjecting the spring to any detrimental lateral bending effects.

Hence my spring actuating device as applied to self-raising tops for automatically returning such a frame structure together with its cover fabric into open extended position, affords an outstanding advantage in that it enables 45 the described tensioning means to sustain a substantially continuous or accumulative raising effort throughout the initial range of top opening movement. Upon reaching this position, said springs will already have 50 lifted the top elements against gravity and imparted the impetus required for horizontally carrying said elements into their fully extended position. Not only is the initial thrust required for self-raising top purposes 55 considerably reduced over conventional devices of this type, but a further betterment is attained through the fact that when my primary spring stretching member gradually loses its purchase effort because of decreasing 60 spring stretch, the supplemental spring mem-

ber is made to come into effective action, thus supplementing any waning of spring actuating effort and maintaining a substantially steady initial opening urge behind the collapsed top members until an almost fully extended position has been reached. Thereupon the partially released spring 17A still exerts a pull upon the primary arm 15C and this lifting moment is taken up by the closed knuckle joint 8C as disposed between the aligned side 75 rails 8A and 8B.

Fig. 5 indicates a modified application of the same underlying principle, except that in this instance the rear end of the actuating spring 18A is shown attached to the stretching member 10A which is here fashioned into a pendant as applied to the brace link 10, and serves essentially the same purpose as that previously described in connection with the alternative element 15C. The spring 80 proper is also modified somewhat in that a helical compression spring 18A has been substituted; the compression type of spring affords the advantage of obviating any permanent set in the coil pitch by limiting the 85 maximum stress that can be imposed when its coils are fully closed.

Fig. 6 is similar to Fig. 5 except that it shows still another mode of storing motive power in a resilient member for self-raising 90 top purposes. In this instance, a non-metallic or rubber-like elastic 19A is disclosed, which is preferably formed into a link shape having enlarged end bosses equipt with apertures. These apertures may be reenforced 95 with metallic thimble bushings 19C and 19C' which in turn carry the tie links 19D and 19D' respectively, as shown.

It is further pointed out that the herein-before described self-raising top devices are 100 preferably but not necessarily used in conjunction with an auxiliary lifting spring such as 20A shown in Figs. 1 and 2. For this purpose one of the standards 2B may be provided with an offset arm such as 20B, which engages 105 one end of said spring 20A, while the other spring end may be fixedly secured to the body by the pivot 20C or in any other suitable manner.

This auxiliary spring element 20A may be used to advantage in simultaneously lifting the interconnected top standards about their respective props 4 while the spring 17A automatically separates and throws forward the other interconnected top members with respect to such rising standards. As a result, the top as a whole may be rapidly and efficiently extended without substantial aid other than releasing the motive power stored in the various top raising springs. It will be apparent that the weight of the top parts assists in overcoming the resistance of the springs opposing the collapsing movement, and since my improved disposition of spring 120 devices provides for a virtually uniform re- 125

sistance, the top may readily be crashed with the minimum of exertion on part of the attendant.

Having described the details of my top structure and its self-raising features, it is thought the mode of operation will readily be understood from the previous disclosures. As to the self-raising devices, reference to Fig. 2 will indicate that both the actuating spring 17A and the auxiliary spring 20A assume their maximum stretched relations when the top is collapsed, in which position the crashed top elements are intended to be retained in place by suitable means such as buckle strap 22 or the like, which may be secured in place to the body pivot 20C. Upon releasing such retaining means, the top frame together with its top covering under the urge of both said springs, will immediately be thrown upwardly and forwardly into extended position, whereupon the outrigger crown 8D may be attached to each of the stanchions 21 and locked in place. It will be evident that this operation may be expeditiously performed by unskilled automobile users and hence affords a convenient means for securing the full benefit of collapsible one-man tops and truly making same function as such.

It will be observed that by virtue of the system of strap links 15 and 16, the top may be folded as a unit by lifting outrigger crown 8D. The effect of such lifting is to break the rule joint 8C and this in turn actuates the described guide links in unison with such movement, said joint 8C being made to swing backwardly and downwardly toward the fulcrum iron 4. In their completely collapsed position, the top members assume the folded relation shown in Fig. 2, when the maximum of lifting energy will be stored within both the springs 17A and 20A.

Although a specific embodiment and shape of top structure have herein been described in connection with my self-raising top devices, I do not wish to be limited to any particular arrangement or form of parts, since various changes may be resorted to such as introducing an additional intermediate bow or by varying the embodiment of my spring stretcher arms into various equivalent forms other than as an extension member of some particular element of the disclosed top structure, all without departing from the spirit and scope of my invention, heretofore described and more particularly pointed out in the appended claims.

I claim:

1. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to

the standards, a bipartite main bow comprising an outrigger hoop and complementary side rails respectively pivoted to a medial portion of the support bow legs, a pair of brace links respectively pivoted to the side rails and to the standards, an intermediate bow pivotally mounted across said rails, a lever fulcrumed between its ends upon one of said support bow legs and of which lever one end portion is pivotally adjoined to the intermediate bow, and resilient means extending between the last named bow and the other end portion of said lever, said means being placed under tension when the top is folded for automatically extending the top with respect to said standards.

2. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to a medial portion of the support bow legs, an intermediate bow having its legs respectively pivoted to said rails and of which one such leg is extended beyond its pivotal mounting, a lever fulcrumed between its ends upon one of the support bow legs and of which lever one end portion is pivotally adjoined to said intermediate bow member, spring means floatingly stretched between said extended portion of the intermediate bow and the other end of said lever, and swivel link means interposed between one end of said spring and its cooperating stretching member.

3. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to a medial portion of the support bow legs, an intermediate bow having legs respectively pivoted to said rails, a lever fulcrumed between its ends upon one of the support bow legs and of which lever one end portion is pivotally adjoined to the intermediate bow, and coiled spring means floatingly disposed between the last named bow and the other end portion of said lever, the coils of said spring means being maintained in a substantially rectilinear stretched relation while the top is being folded.

4. In a top structure of the self-raising type for vehicle bodies or the like adapted to be automatically shifted between collapsed and raised positions, a pair of spaced

- standards pivotally propped to the body and serving to support the raised top, a support bow having its legs respectively pivoted to the standards, a bipartite main bow comprising an outrigger hoop and complementary side rails respectively pivoted to a medial portion of the support legs, an intermediate bow having legs respectively pivoted to said rails, a lever fulcrumed between its ends upon one of the support bow legs and of which lever one end portion is pivotally adjoined to the intermediate bow, resilient means stretched between said last named bow and the other end portion of said lever, and a cooperating auxiliary spring means engaging one of said standards to exert a lifting tension thereon about its prop, said auxiliary spring and the aforesaid resilient means serving by combined effort to raise and extend the top as a whole. 5. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to a medial portion of the support bow legs, an intermediate bow having legs respectively pivoted to said rails and of which one such leg is extended beyond its pivotal mounting to form an extension, a lever fulcrumed between its ends upon one of the support bow legs and of which lever one end portion is pivotally adjoined to said intermediate bow while the other lever end is disposed in offset alignment relative to said one lever end, and resilient means floatingly stretched between said offset lever end and the intermediate bow extension, said means being adapted to exert an accumulative top-raising effort with respect to both said offset lever end and the aforesaid extension. 6. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to a medial portion of the support bow legs, an intermediate bow having its legs respectively pivoted to said rails and of which one such leg is provided with an extension adapted to swing through a relatively wide angular range when the top is shifted between extreme positions, a lever fulcrumed between its ends upon one of the support bow legs and of which lever one end portion is pivotally adjoined to said intermediate bow while the other lever end is disposed in offset alignment relative to said one lever end and adapted in all of its positions to a- posed in offset alignment relative to said one lever end and adapted in all its positions to afford an effective top lifting purchase, and resilient means floatingly stretched in maintained rectilinear relation between said offset lever end and the intermediate bow extension, said means being adapted to approach virtual alignment relative to the longitudinal axis of said extension member whenever the latter is rocked into either of its extreme shifted positions. 7. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to said rails and of which one such leg is provided with an extension adapted to swing through a relatively wide angular range when the top is shifted between extreme positions, a lever fulcrumed between its ends upon one of the support bow legs and of which one end portion is pivotally adjoined to said intermediate bow while the other lever end is disposed in offset alignment relative to said one lever end, and resilient means floatingly mounted in maintained rectilinear relation between said offset lever end and said bow extension, said means being adapted to approach virtual alignment relative to the longitudinal axis of said extension member whenever the latter is shifted into either of its extreme shifted positions and to assume an approximately perpendicular relation with respect to both the extension and said offset lever end when the last named members are shifted into their respectively mid-positions. 8. In a top structure of the self-raising type for vehicle bodies or the like adapted to be automatically shifted between collapsed and raised positions, a pair of spaced standards pivotally propped to the body and serving to support the raised top, a support bow having its legs respectively pivoted to the standards, a bipartite main bow comprising an outrigger hoop and complementary side rails respectively pivoted to a medial portion of the support bow legs, an intermediate bow having its legs respectively pivoted to said rails and of which one such leg is provided with an extension adapted to swing through an angle when the top is shifted between extreme positions, a lever fulcrumed between its ends upon one of the support bow legs and of which lever one end portion is pivotally adjoined to said intermediate bow while the other lever end is disposed in offset alignment relative to said one lever end and adapted in all of its positions to af-

ford an effective top lifting purchase, and floating resilient means stretched between said offset lever end and said bow extension, said means being disposed to maintain a continuous top raising urge upon said other lever end and to simultaneously exert a supplementary urge upon said bow extension

when the latter is shifted into an intermediate position and which last named urge acts accumulatively in support of said continuous urge.

In testimony whereof, I have herewith set my hand this 22nd day of March, 1926.

LYNN EVANS.
